(57) **CLAIM**

We claim the ornamental design for a container accessory, as shown and described.

DESCRIPTION

FIG. 1 is a first perspective view of a container accessory, according to the present design;

FIG. 2 is a second perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a perspective view of the container accessory shown in a position of use with an exemplary container; and, FIG. 10 is another perspective view of the container accessory shown in another position of use with an exemplary container.

The broken lines are shown for the purpose of illustrating parts of the article as well as environmental subject matter of an exemplary container and form no part of the claimed design.

1 Claim, 9 Drawing Sheets
